Primary Examiner — Manpreet Matharu*Assistant Examiner* — Suzanne Tisdell(74) *Attorney, Agent, or Firm* — Marshall, Gerstein & Borun LLP(57) **CLAIM**

The ornamental design for a battery for a remote controlled toy, as shown and described.

DESCRIPTION

FIG. 1 is an enlarged front elevation view of a battery for a remote controlled toy.

FIG. 2 is an enlarged rear elevation view of the battery for a remote controlled toy seen in FIG. 1.

FIG. 3 is a left elevation view of the battery for a remote controlled toy.

FIG. 4 is a right elevation view of the battery for a remote controlled toy.

FIG. 5 is a top plan view of the battery for a remote controlled toy.

FIG. 6 is a bottom plan view; and,

FIG. 7 is an isometric view of the battery for a remote controlled toy.

The broken lines represent portions of the battery for a remote controlled toy that form no part of the claimed design.

1 Claim, 7 Drawing Sheets(56)
